ATTORNEY

UNITED STATES PATENT OFFICE.

CHACE D. GILMORE, OF HIGHLAND PARK, MICHIGAN.

SHAKER.

1,250,848.

Specification of Letters Patent. Patented Dec. 18, 1917.

Application filed November 29, 1916. Serial No. 134,155.

To all whom it may concern:

Be it known that I, CHACE D. GILMORE, a citizen of the United States, residing at Highland Park, in the county of Wayne and 5 State of Michigan, have invented a new and useful Shaker, of which the following is a specification.

This invention relates to shakers, and is in the nature of an improvement in part and 10 a continuation in part of the invention embodied in the application filed by me February 24, 1916, Serial No. 80,195.

The object of the present invention is to provide a shaker in which there are a plurality of chambers whereby a single shaker 15 may be utilized for two or more condiments, or the like.

In particular it is an object of my invention to provide a shaker which is simple in 20 its parts, quickly operated, in which the several condiments or the like, are kept separate, and in which the operating parts or mechanism will not sacrifice the artistic features of the shaker.

Another object of the invention is to provide a construction in which there is no 25 danger of the operating ferrule or annular member jamming the perforated top of my shaker, thereby insuring the free and easy 30 scraping of the valve thereagainst.

A further object of the invention is to provide certain detail improvements in a construction as will be more fully described and pointed out hereinafter.

In the particular embodiment of my invention here illustrated, the perforated top is relatively fixed and does not constitute a part of the actuating mechanism for the valve as in certain modifications of my co-pending application. However, it is to be understood that the invention, in so far as the improved features of construction are concerned, is not to be limited to a top of such construction.

By reference to the accompanying drawings and the following description, it will be seen that the present construction of my device is a very simple one, and very compact as well as durable, and that the device 50 is highly artistic, the presence of operating mechanism in no manner impairing the artistic features of the shaker, and I consider this one of the characteristics of my invention. It should be noticed that the

operating parts with the exception of the 55 rotatable ferrule are entirely concealed from view.

Referring to the drawings:

Figure 1 is an elevation of the device with a portion of the outer rotatable ferrule 60 broken away for the sake of clearness.

Fig. 2 is a sectional elevation thereof.

Fig. 3 is a similar sectional elevation taken at right angles to that of Fig. 2.

Fig. 4 is a top plan view of the device. 65

Fig. 5 is a bottom plan.

Fig. 6 is a sectional view on the line 6—6 of Fig. 2, looking in the direction of the arrow.

Fig. 7 is a cross section on the line 7—7 70 of Fig. 3, looking in the direction of the arrow.

Fig. 8 is an enlarged detail sectional view, showing the connection between the valve shaft and the rotatable ring mounted upon 75 the body portion of the shaker.

Fig. 9 is a plan view of the rotatable ring used in the embodiment of the invention here shown.

Fig. 10 is an elevation thereof.

Fig. 11 is a detail perspective view of the valve shaft.

Fig. 12 is a detail perspective view of the angular piece used for transmitting motion from the rotatable ring to the valve shaft. 85

In the embodiment of my invention here shown, I have designated the body portion of the shaker by the reference numeral 1, the upper portion of the shaker terminating in a semi-spherical or dome-shaped top or cap 90 2, provided with perforations 3 all of substantially uniform and medium size. The body portion 1 is provided with a partition 4 dividing the shaker into the chambers 5 and 6.

A transversely extending shaft 7 is journaled upon the body portion of my present device on a line substantially coincident with the diameter of the semi-spherical top 2. The ends 8 of the shaft project through 100 the body portion or casing of the shaker. The shaft in the present instance is provided with a longitudinally extending slot 9 adapted to receive the semi-circular valve 10. This valve has a curved edge 11 the curvature of which fits the inner surface of the top and acts as a scraper to scrape any condiment from the top or the perforations into its 105

proper chamber. The shaft 7 extends substantially in alinement with the upper edge of the partition 4, whereby the valve may be swung from one side of the perforations 5 to the other, closing either of the chambers.

As will be apparent from an inspection of the drawing, the perforations are of uniform size, the same perforations being used to allow the escape of the condiment from either chamber according to the position of the valve. The construction here shown is characterized by great simplicity and economy of material. The body portion of the casing 1, in the present instance, where it joins with the cap or top is provided with a bearing shoulder 12 upon which rests the ring 13. This ring 13 is located below the ends of the shaft 7, whereby it is securely retained in place between said ends and said bearing, (Fig. 3). The ring 13, in the present instance, is provided along its inner periphery with vertically extending projections 14 and 15 struck up therefrom, (Figs. 9 and 10), which project above the ends of the shaft 7 and coöperate therewith to form stops to limit the rotation of the ring 13. The arrangement is such that the rotation will be prevented when the valve 10 closes either chamber.

As is shown in Fig. 9, to one side of the projection 15 there is a recess 16 upon the inner side of the ring and a hole 17. The end of the shaft 7 adjacent this recessed part of the ring 13 is slotted, as shown at 18, Fig. 11.

An angular piece 19 of non-corrodible wire or other material, and of a construction such as is shown in Fig. 12, is provided with a horizontal portion or pintle 20 rotatably mounted within the opening 17, and a vertically extending portion 21 slidably working in the slot 18. It will be seen that the rotation of the ring 13 will cause the rotation of the shaft 7 on its axis through the connection of the piece 19. The recess 16 of the rotatable ring through which the portion 21 of the piece 19 projects allows the free movement of the piece back and forth. Mounted upon the ring 13 is an additional projection 22, which is also integrally formed, being cut out from the material constituting the ring 13, (Fig. 9). The projections, 14, 15 and 22, are all of the same height, and are spaced from each other, and the three perform a function, in addition to the function already described in regard to the projections 14 and 15.

To conceal and protect the rotatable ring 13, and its connection with the shaft, and to provide an exteriorly arranged annular operating member therefor, an annular ferrule 23 is adapted to inclose and be spun under, as shown at 24, the ring 13. The ferrule 23 tightly engages the ring 13 and to rotate the latter it is necessary to first rotate

the ferrule. The top wall 25 of the ferrule projects inwardly toward and surrounds the cap beyond the perforations.

The projections 14, 15 and 22 engage the top wall 25 of the ferrule, and space the same from said member and prevent it from descending and jamming tight against the top or cap 2, which jamming would result in the denting of the cap, and cause the defective operation of the valve. 75

It is thought that the operation of my device will be obvious from the above description. When the ferrule 23 is rotated, the ring 13 is rotated, and the connection of the ring 13 with the shaft 7, causes the valve 80 to assume a position over either one chamber or the other closing the same. As the ferrule is rotated in one direction, the stop 15 will contact with one end 8 of the shaft and prevent further rotation, and as the ferrule 85 is rotated in the reverse direction, the projection 14 will engage the opposite end 8 of the shaft and prevent further rotation in the opposite direction. As the valve moves from one position to the other, it sweeps and scrapes across the inside of the spherical portion of the top, returning any condiment thereon back to its proper chamber and thoroughly cleaning it, so that the condiment in the other chamber will not mix with the first 90 condiment when it escapes.

As was fully described in my co-pending application, the several condiments are inserted at the bottom, and for this purpose I have provided a suitable bottom 26 provided with openings 27 and 28 communicating with the chambers. Below this bottom is a rotatable member 29 provided with a single opening 30 adapted to register, in the manner described in the co-pending application, 105 with either of the openings 27 or 28. For the purposes of rotating the member 29, I have fixed to the same a transversely extending rod or handle 31. As the construction of the lower portion of the device herein 110 shown does not constitute part of the present invention, a further description thereof is deemed unnecessary, as reference may be had to the co-pending application above mentioned. 115

While I have shown and described one embodiment of my invention, it is to be understood that I do not desire to be limited to the details of construction herein shown, and described, for obvious modifications and changes will be apparent to any one skilled in the art.

What is claimed is:—

1. In a device of the character described, a body portion having a partition dividing the same into two chambers adapted to hold condiments of different natures, and a normally fixed perforated cap, a single valve pivoted at one edge adjacent the upper edge of said partition and having its oppo- 125

site edge closely fitting the inner side of said cap thereby acting as a scraper, and means for swinging said valve across said cap beyond the perforated portion thereof from 5 one side to the other to open communication between the entire perforated portion of the cap and each individual chamber as desired, so that the contents of each chamber may be discharged through all the perforations, said 10 means for swinging said valve being independent of said cap and having a direct connection with said valve.

2. In a device of the character described, a body portion having a plurality of chambers for holding condiments of different natures, and a perforated normally fixed cap, a valve for controlling the escape of condiment from each chamber through said 15 perforated cap, and a rotatable ferrule encircling said body portion and having a direct connection with said valve for operating the same.

3. In a device of the character described, a body portion having a plurality of chambers for holding condiments of different natures, a perforated cap, a valve pivoted upon a horizontal axis for controlling the escape of condiment from each chamber through said 20 perforated cap, a ferrule encircling said body portion adjacent said cap and rotatable about a vertical axis, and a direct connection between said ferrule and said valve for operating the same, said connection being independent of said cap.

35 4. In a device of the character described, a body portion having a plurality of chambers and a rigid perforated cap, a valve pivoted upon a horizontal axis for controlling said chambers for opening communication 40 between the same and the perforated cap, a ferrule encircling said body portion adjacent said cap and rotatable about a vertical axis, and a direct connection between said ferrule and said valve, said connection slidably engaging said valve.

45 5. In a device of the character described, a body portion having a partition dividing the same into two chambers for holding condiments of different natures, and a perforated rigid cap or top, a single valve pivoted at one edge adjacent the upper edge of said partition and having its opposite edge fitting closely to the inner side of the top thereby acting as a scraper, and a rotatable 50 annular member encircling said body portion and having a direct connection with said valve for operating the same independently of the perforated top, said valve being adapted to swing from one side to the other to open communication between the chambers and the entire perforated portion each time.

60 6. In a device of the character described, a body portion having a plurality of chambers and a perforated normally fixed cap or

top, a valve controlling communication between said chambers and cap or top, a rotatable ring mounted upon and encircling said body portion, a direct connection between said rotatable ring and said valve whereby 70 the rotation of the ring actuates the valve, and a ferrule inclosing said rotatable ring, and engaging the same to effect the rotation of the latter upon the turning of the ferrule.

7. In a device of the character described, a 75 body portion having a plurality of chambers, and a rigid perforated cap or top, a valve controlling said chambers for opening communication between the same and the perforated top, a rotatable ring encircling 80 said body portion, means connected to said ring and slidably engaging said valve for actuating the same, and a rotatable annular member for actuating said ring.

8. In a device of the character described, 85 a body portion having a plurality of chambers and a perforated cap or top, a valve controlling communication between said chambers and said top, said valve comprising a transversely extending shaft provided 90 with a slot at one end thereof, a rotatable annular member mounted upon the outside of said body portion, and means pivoted to said rotatable member and slidably engaging the slot of said shaft, whereby the annular member rotates the shaft directly 95 through said means.

9. A device of the character described, a body portion comprising a plurality of chambers and a perforated cap or top, a 100 valve controlling communication between said chambers and said cap or top, a rotatable ring encircling the body portion for actuating said valve, means for limiting the rotation thereof, a ferrule inclosing said 105 rotatable ring, and means on said rotatable ring for preventing said ferrule from jamming said perforated top.

10. In a device of the character described, a body portion having a plurality of chambers and a perforated cap or top, a valve controlling communication between said chambers and cap, a rotatable ring supported upon said body portion and encircling the same, said ring having vertically 110 extending projections, a connection between said ring and said valve whereby the movement of the ring actuates the valve, and a ferrule mounted upon said ring and inclosing the same, said vertically extending projections engaging the top wall of the ferrule 115 and preventing the same from jamming the cap.

11. In a device of the character described, a body portion having a plurality of chambers and a perforated cap or top, a valve controlling communication between the several chambers and the cap or top, and having a transversely extending shaft projecting beyond the body portion, a rotatable ring 120 125

130

- mounted upon and encircling said body portion, said ring being provided with spaced apart vertically extending projections, said shaft having its ends lying in the path of said projections, whereby the rotation of the ring is limited in both directions, and a connection between said rotatable ring and said shaft whereby the valve is actuated by said ring.
- 10 12. In a device of the character described, a body portion having a plurality of chambers and a perforated cap or top, a valve controlling communication between said chambers and the cap or top, and having a trans- 45 versely extending shaft projecting beyond said body portion, a rotatable ring mounted upon and encircling said body portion and provided with projections adapted to engage the ends of said shaft to limit the rotation of said ring, an inclosing ferrule for operating said ring, the top of said ferrule being spaced from said ring by said projections whereby the jamming of the cap is prevented, and a connection between said rotatable ring and said shaft for actuating the valve.
- 15 13. In a device of the character described, a body portion having a plurality of chambers and a perforated cap or top, a valve controlling communication between said chambers and said cap or top, and having a transversely extending shaft projecting beyond the body portion, one end of said shaft being slotted, a rotatable annular member mounted upon and encircling said body portion, stops adapted to engage said shaft
- 20 for limiting the rotation of said member, and an angular piece pivoted at one end to said rotatable member and its other end projecting through the slot of the shaft and having a slidable engagement therewith, where- 40 by the rotation of said member actuates said valve.
- 25 14. In a device of the character described, a body portion having a plurality of chambers, and a perforated cap or top, a valve 45 controlling communication between said chambers and said cap or top, and having a transversely extending shaft projecting beyond said body portion, said shaft having one end thereof slotted, a rotatable ring 50 mounted upon and encircling said body portion and provided with projections, an angular piece pivoted at one end to said rotatable ring and having its other end slidably en- 55 gaging the slot of the shaft, whereby the rotation of said ring actuates said valve, and an actuating ferrule inclosing said member and having its top wall overhanging the face of the cap or top, said projections per- 60 forming the dual function of acting as stops to limit the rotation of said ring and of preventing the jamming of the top wall of said ferrule against the perforated top.
- 30 In testimony, that I claim the foregoing as my own, I have hereto affixed my signature in the presence of two witnesses.
- 35 CHACE D. GILMORE.
